CLAIM

The ornamental design for a disc drive assembly, as shown and described.

DESCRIPTION

FIG. 1 is a perspective view of the disc drive assembly showing our new design;

FIG. 2 is a front elevational view thereof on an enlarged scale;

FIG. 3 is a back view thereof on an enlarged scale;

FIG. 4 is a left elevational view thereof on an enlarged scale;

FIG. 5 is a right elevational view thereof on an enlarged scale;

FIG. 6 is a top view thereof on an enlarged scale; and

FIG. 7 is a bottom view thereof on an enlarged scale.
